UNITED STATES PATENT OFFICE.

JOHN D. PRICE AND WALTER HENRY DRAKE, OF CLEVELAND, OHIO.

SHOE AND METHOD OF MAKING SAME.

Application filed October 31, 1922. Serial No. 598,131.

To all whom it may concern:

Be it known that we, JOHN D. PRICE and WALTER H. DRAKE, citizens of the United States, residing at Cleveland, in the county of Cuyahoga and State of Ohio, have invented certain new and useful Improvements in Shoes and Methods of Making Same, of which the following is a specification.

This invention relates to shoe sole attaching means and has for an object to provide improved means for attaching the various elements of a sole to the upper.

A further object of the invention is to provide a shoe sole attaching means embodying in its organization a welt with improved means for connecting together the welt, the insole and the upper.

A further object of the invention is to provide in a shoe sole attaching means an insole, a welt, a liner for the insole and an upper, the liner and the upper having their edges inserted between portions of the insole and the welt and secured therein by some driven, or penetrating, or impaling instrumentalities.

A further object of the invention is to provide a shoe sole attaching means which shall operate successfully, though not necessarily exclusively, with the shoe construction embodying a metallic or like sole member as disclosed in co-pending application Sr. No. 598,132, filed on even date herewith.

With these and other objects in view, the invention comprises certain novel parts, elements, units, combinations, constructions and methods as disclosed in the drawings together with mechanical, functional and method equivalents thereof, as will be herein-after more fully described and claimed.

40 In the drawings:

Figure 1 is a transverse sectional view on a greatly enlarged scale through a shoe sole and upper attached in accordance with and by the practice of the present method.

45 Figure 2 is a detail sectional view showing a modified type wherein the welt and insole are integral.

Figure 3 is a further modification wherein the penetrating or impaling member is inverted.

50 Figure 4 is a further modification showing the penetrating members as separated instead of formed as staples.

Figure 5 is a still further modification showing the separation penetrating members 55 inverted.

Like characters of reference indicate corresponding parts throughout the several views.

In the usual and ordinary construction of 60 shoes, the sole 10 is attached to the upper 11 by the use of a welt, the sole being stitched to the welt. The present invention follows this general plan and provides a welt 12 which is stitched by the stitching X, to the sole 10. The manner of connecting the welt and the upper, however, differs in the present invention from the present practice. In 65 this invention, an insole 13 is employed, the edges being skived to an attenuated edge 14, preferably also forming a shoulder 15. The welt 12 is also skived on an incline at 16 so that the lines of skiving of the insole 14 and the welt 12 are substantially parallel and spaced slightly apart to receive the edges 70 17 of the upper 11 and the edges 18 of a liner 19. This liner 19 in the practice as at present proposed will cover and inclose a plate 20 of some relatively stiff, springy or 75 resilient material, such for instance as a metal plate. The metal plate, however, forms no part of the present invention except as it is adapted for use in conjunction with the sole attaching means described and claimed herein.

The edges 17 and 18 of the upper 11 and liner 19 respectively being positioned between the welt 12 and the inclined edge of the insole 13 in laminated position will be secured by means of penetrating members 80 inserted through the insole and through the welt and the two laminated edges. Preferably, also wires or similar members 21 and 22 will be laid in grooves or furrows, the former in a groove or furrow cut in the welt 12 and the latter in a groove or furrow formed in the insole, as shown in the cross sections figures of the drawings. These wire members 21 and 22 will, it is intended, extend entirely around the sole adjacent the periphery and positioned as indicated at Figure 1. These wires 21 and 22 will serve not only for adding resiliency and springiness to the sole and maintaining the shape 90 of the sole under all conditions, but serve 95 also as a means for resisting the tendency of 100 105

the penetrating members to pull. Instead of making the welt 12 as a separate part, a welt portion 12' may be formed directly upon and as part of the insole 13'. In all other respects the structure so formed will correspond to the structure shown at Figure 1 and may also employ the various fastening means to be hereinafter more fully described.

- 10 As shown at Figure 1, staples 23 are employed which are inserted through the insoles 13 or 13' as an initial step. The penetrating points of these staples will extend substantially at right angles to and beyond the face of the insole. The liner 19 over the plate 20, if employed, will then have its edges turned over the edge of the insole and impaled upon the upwardly extending points of the several staples which are spaced about adjacent the periphery of the sole. The upper, with, of course, a lining if employed but not shown, will then be placed in position and its edges turned over and likewise impaled upon the points of the staple and pressed downwardly upon and against the inturned edges of the liner 19. The welt 13 will now be placed in position by impaling upon the same points. The grooves of the insole and the grooves of the welt are now in the relation shown at Figure 1 and just within the lines of the points of the staples, so that, when the points of the staple are clinched, as indicated at 24 and 25, such clinched ends will be directly upon the wires. It is obvious that this part of the construction will be completed before the sole 10 is placed in position and stitched by means of the stitching X.

To vary the construction as circumstances 40 may make desirable, the staple 26, see Figure 3, may be inserted from the under side of the insole after all of the parts with the exception of the outer sole have been assembled and clinched in any approved manner 45 as against the metal plate 20. Also, a further variation may employ nails or like members 27, see Figure 4, driven through the insole in the same manner as described in regard to the staples 23 and employed in 50 like manner in all other particulars, or the same result may be accomplished by the construction as shown at Figure 5 with the nails 28 driven upwardly from the bottom in accordance with the employment of the staple 55 26 and having their ends also clinched against some surface, as the metal plate 20.

In any and all of these constructions, it is 60 apparent that the edges of the liner and the edges of the upper are turned inwardly and under a beveled portion of the insole and that the fastening members are inserted through the insole and through the inturned edges and that the welt, whether integral with the insole or separate, will also be secured firmly in position and relation to the

other parts by these fastening members and that in any and all types of fastening members or other relations the reinforcing wires will be held in their grooves or furrows in the insole and the welt or welt portion by means of such fastening members. With a shoe constructed in accordance with this invention, with the liner turned under and firmly secured, it is obviously impossible for any of the fastening members to protrude through the bottom of the shoe into the shoe chamber to annoy the wearer as is found common in foot wear.

What we claim is:

1. The method of attaching a shoe sole and upper consisting in turning the edges of the upper inwardly and under an insole, employing a welt beneath the inturned edge and connecting the several parts together by penetrating members substantially perpendicular to the plane of the insole. 80

2. The method of attaching a shoe sole and upper consisting in folding under the edge of an insole the edges of a liner for said insole, folding under the edges of the liner the edges of the upper, embodying a welt under said infolded edges and inserting fastening members through said welt strip, said inturned edges and said insole substantially perpendicular to the plane of the insole. 90

3. The method of attaching a shoe sole and upper consisting in forming a rabbet about the edge of an insole, folding the edges of a liner from the upper side of the insole about the edges of said insole and into said rabbet, turning inwardly the edges of the upper to bear upon the inturned edges of the liner also within the rabbet, inserting the inner edge of a welt strip into the rabbet bearing upon the inturned edges of the upper and liner, and inserting fastening members through the insole, the said inturned edges and the said welt strip substantially perpendicular to the plane of the insole. 100

4. The method of attaching an upper to a sole consisting in forming a rabbet about the edge of an insole, placing a liner upon the top of the insole and turning its edges under and into the rabbet, turning the edges of the upper inwardly within the rabbet and upon the inturned edges of the liner, employing a welt strip which is inserted into the rabbet bearing upon said inturned edges, forming a groove about the welt strip, inserting a reinforcing wire in the groove, and inserting fastening members to pass through said welt strip, said inturned edges and said insole and to bear upon said wire to maintain the same in its groove. 115

5. A shoe comprising an insole having a marginal rabbet with an inclined surface and a furrow formed in the under side of said insole, spaced substantially equidistant 125

from said rabbet, a liner carried upon the surface of the insole and having its ends turned under the inclined edge of the insole and seated within the rabbet, an upper having 5 its edges inturned within the rabbet and positioned upon the inturned edges of the liner, a welt strip bearing upon the inturned edges and provided with a groove extending about said strip, substantially equidistant 10 from the groove of the insole, and fastening means inserted through the welt, the inturned edges and the insole and extending across said grooves.

6. A shoe comprising an insole having 15 a marginal rabbet with inclined surface, a liner for the insole with its edges turned about the edge of the insole and into the rabbet, an upper having its edges turned into the rabbet and bearing upon the edges 20 of the liner, a welt strip bearing upon said inturned edges and positioned within the rabbet, said welt strip and insole having furrows formed substantially equidistant throughout their course and upon opposite 25 sides of the abutting of the welt strip with the insole, wires positioned in the furrows, and fastening members inserted through the welt, the inturned edges and the insole and bearing upon the wires.

7. The method of attaching a sole to an upper consisting in forming about the edge of an insole a rabbet having an inclined surface, inserting through the said insole staples with their penetrating points extending below the surface of the insole, one of said points extending through the rabbet, placing upon the insole a liner, turning its edges inwardly and impaling them upon the points of the staples which are inserted through the 35 rabbet, turning inwardly the edges of the upper and impaling them upon the same penetrating points, impaling upon said points the inner edge of a welt strip proportioned to be accommodated in the rabbet 40 and bear upon the inturned edges, forming in the insole and welt strip furrows each adjacent one of the points of said staples, placing wires in the furrows and clinching the points of the staples over said wires.

8. The method of attaching a shoe sole and upper consisting in forming about the edge of an insole a rabbet having an inclined face, turning over the edge of the insole the marginal edges of a liner and positioning such edges within the rabbet, turning inwardly the edges of the upper and positioning them within the rabbet, inserting into the rabbet a welt strip to bear upon said inturned edges, forming furrows about said insole and welt

strip upon opposite sides of the dividing line, 60 and employing a staple penetrating the insole, the inturned edges and the welt and bearing upon the said wires.

9. A shoe comprising an insole, a liner for the insole with its edges turned under and positioned within a rabbet formed in the edge of said insole, an upper having its edges turned inwardly and positioned within the rabbet and upon the inturned edges of the liner, a welt strip bearing upon the inturned edges, reinforcing wires embedded in said welt strip and said insole and spaced upon opposite sides of the dividing line, and staples penetrating said insole, said edges and said welt strip and bearing upon the reinforcing wires, maintaining said wires in fixed relation relative to each other.

10. The method of attaching a shoe sole and upper consisting in turning the edges of the upper inwardly and under an insole, inserting a welt strip beneath the inturned edge and connecting the several parts together by penetrating members spaced upon opposite sides of the inner edge of the welt and connected by a part substantially parallel 85 with the plane of the insole.

11. The method of attaching a shoe sole and upper consisting in folding under the edge of an insole, the edges of a liner for said insole, folding under the edges of the liner the edges of the upper, applying a welt strip to the under side of said infolded edges and inserting penetrating members through said welt strip, said inturned edges and said insole and through the insole, said 95 penetrating members being connected by a part substantially parallel with the plane of the insole.

12. The method of attaching a shoe sole and upper consisting in forming a rabbet 100 about the edge of an insole, folding the edges of a liner from the upper side of the insole about the edges of said insole and into said rabbet, turning inwardly the edges of the upper to bear upon the inturned edges of the liner also within the rabbet, inserting the inner edge of a welt strip into the rabbet bearing upon the inturned edges of the upper and liner, and inserting connected penetrating members one member passing 105 through the insole, the said inturned edges and the said welt strip and the other through the insole only within the lines of the welt.

In testimony whereof we affix our signatures.

JOHN D. PRICE.
WALTER HENRY DRAKE.
